UNITED STATES PATENT OFFICE.

PHILLIP W. BAIR, OF KANSAS CITY, KANSAS.

DAVENPORT.

1,276,859.

Specification of Letters Patent. Patented Aug. 27, 1918.

Application filed November 19, 1917. Serial No. 202,723.

To all whom it may concern:

Be it known that I, PHILLIP W. BAIR, a citizen of the United States, residing at Kansas City, in the county of Wyandotte 5 and State of Kansas, have invented a certain new and useful Improvement in Davenports, of which the following is a specification.

My invention relates to improvements in 0 davenports.

My invention is particularly adapted to davenports of the type having a foldable bed bottom.

One of the objects of my invention is to 15 provide a davenport with a folding bed bottom of novel construction, which may be quickly and easily moved to the folded or the stretched out position, which is simple in construction, strong, durable and not 20 likely to get out of order, which is cheap to manufacture, and which is efficient in operation.

My invention provides further novel 25 means for supporting the bed bottom in the folded position and which aids the operator to unfold the same.

My invention provides further a novel 30 pillow rest, and also novel means for cooperatively connecting the pillow rest and the adjacent legs of the bed bottom, whereby they may be simultaneously moved to and from the folded position.

Other novel features of my invention are hereinafter fully described and claimed.

35 In the accompanying drawings, which illustrate the preferred embodiment of my invention,

Figure 1 is a top view of my improved 40 davenport showing the bed bottom stretched out, the mattress being removed.

Fig. 2 is a side elevation, partly broken away, of what is shown in Fig. 1.

Fig. 3 is an enlarged side elevation of the 45 pillow rest and adjacent legs and a portion of the bed bottom, the folded and operative positions being shown respectively in solid and dotted lines.

Fig. 4 is a rear end elevation of the davenport, partly broken away, showing the 50 bed bottom folded and the swinging back member in the elevated or open position.

Fig. 5 is an enlarged inside elevation of a part of the bed bottom.

Fig. 6 is an enlarged perspective of a portion of the inner section of the bed bottom. 55

Fig. 7 is a side elevation, partly broken away, showing the bed bottom partly folded.

Fig. 8 is a side elevation showing the bed bottom and mattress fully folded and the hinged back member closed. 60

Similar reference characters designate similar parts in the different views.

The box frame is provided with the usual end members 1 having respectively hinged thereto arms 2, and which are connected by the usual back frame 3 which, between the arms 2 forms with the side members 1 a pocket adapted to receive a portion of the mattress 4 and a portion of the bed bottom when the latter is folded as shown in Fig. 8. 70

This pocket is adapted to be closed by an upholstered back member 5, which is hinged at its upper edge to a cross bar 6 which forms a portion of the back of the box frame. 75

The bed bottom, the construction of which is best shown in Figs. 1 to 3, preferably comprises a plurality of sections pivotally connected with each other, so as to be swung from the stretched out position shown in 80 Figs. 1 and 2 to the folded position shown in Fig. 8. These bed bottom sections comprise a seat section having an upholstered seat 7 to the under sides of which, adjacent to its ends respectively are secured two angle 85 bars 8.

Pivoted to the angle bars 8 respectively by means of transverse pins 9 are two angle bars 10 of an intermediate bed bottom section, said bars 10 being pivoted by transverse pins 11 to the adjacent ends respectively of two angle bars 12, which form part of the inner section of the bed bottom. A transverse bar 13 is rigidly secured to the inner ends of the bars 12. A transverse channel bar 14 is secured to the bars 12 adjacent to the pins 11. 95

As shown in Fig. 5, the horizontal flanges of the bars 8 extend inwardly beyond the pins 9, and the horizontal flanges of the bars 10, 12 extend outwardly beyond the pins 11, whereby the seat and intermediate sections 100

cannot break in folding beyond the stretched-out position, but which arrangement permits these sections to fold inwardly with respect to the bars 12, as shown in dotted lines in Fig. 5.

15 designates two angle bars of the outer section of the bed bottom pivoted respectively by transverse pins 16 to the bars 8. The bars 8 extend outwardly beyond the 10 pins 16 so as to have a bearing upon the horizontal flanges of the bars 15, whereby the outer section of the bed bottom is held from swinging inwardly past the straight line position, but is permitted to swing outwardly, as shown in Fig. 7.

The bed bottom carries a mattress support of any desired type, but which preferably comprises a series of jointed longitudinal rods 17 secured to transverse bars 18, said 20 rods and bars having their ends supported by coil springs 19 fastened in the usual manner to the sides and ends of the bed bottom.

The seat 7 is pivoted on a single horizontal axis located, preferably, substantially 25 centrally between the upper and lower sides of the seat, to the box frame. To opposite ends of the seat 7 are respectively secured two plates 21 which are respectively pivoted by transverse pins 20 to two upwardly extending bars 22 which are respectively secured to the end members 1 of the box frame. By means of this arrangement, the seat 7 in either the operative or the inverted position remains in substantially the same horizontal 35 plane.

Referring particularly to Figs. 2 and 3, 23 designates a pillow rest having secured to its ends respectively two plates 24 which are respectively pivoted by two transverse 40 pins 25 to two vertical plates 26 which are secured to the bars 15 respectively.

The plates 24 are provided with gear teeth 27 which mesh with gear teeth 28 provided in two plates 29 which are respectively secured to two legs 30, and which are respectively pivoted to the plates 26 by two transverse pins 31. A transverse bar 32 has its ends secured respectively to the legs 30 and serves as a brace therefore, and, by striking 45 the bars 15, limits the upward movement of the legs.

A coil spring 33 has its ends respectively secured to the plates 24 and 29. The arrangement of said spring is such that it will 50 pass the pivot pins 25 and 31, when the pillow rest 23 and legs 30 swing from the folded position to the open or operative position. This position of the spring 33 enables it to hold the pillow rest and legs 55 releaseably in the open or the folded position, so that they will not be moved accidentally from the position to which they may be adjusted. Two springs 33 are provided, one at each side of the bed bottom.

By having the plates 24 and 29 of each 65 set geared together, the pillow rest 23 and legs 30 are made to move conjointly. By swinging the legs 30 to the closed position, the pillow rest will be swung to the closed position. In the latter position, the pillow 70 rest is adapted to bear against the upper side of the mattress 4, as shown in Figs. 3 and 7, thereby holding the adjacent end of the mattress securely to the bed bottom.

When the bed bottom is to be folded, the 75 legs 30 and pillow rest 23 are folded as shown in solid lines in Figs. 3 and 7, following which the seat member 7 is swung inwardly on the pins 20, thereby swinging inwardly and downwardly to the bars 10 of 80 the intermediate section, thereby forcing downwardly the bars 12, the inner ends of which are respectively supported by two cables 34 which have a running connection with and are supported by two supporting 85 devices comprising preferably two pulleys 35 mounted respectively upon the inner sides of the end members 1. One set of ends of the cables 34 are attached to the seat 7 at opposite ends thereof, the other set of ends 90 of the cables being respectively secured to two plates 36, which are secured respectively to the bars 12 adjacent to the inner ends thereof.

When the bed bottom is being folded, the 95 bars 15 of the outer section are swung outwardly on the bars 8, as shown in Fig. 7, thus bending the mattress 4 outwardly at the hinged connection between the outer and seat sections.

As the bars 8 swing inwardly in folding, they strike the upper edge of a transverse supporting bar 37 having its ends preferably upwardly and downwardly slideable in two guides comprising vertical grooves 38 105 provided one on the inner side of each end member 1. The bar 37 has a yielding support comprising preferably two vertical coil springs 39 having their lower ends attached to the bar 37 and having their upper ends secured respectively to the inner sides of the 110 end members 1.

When the bed bottom is fully folded, as shown in Fig. 8, the bars 8 will have depressed the bar 37, so as to stretch the 115 springs 39, which will thus support a part of the load of the bed bottom and mattress, so as to assist the operator in starting the unfolding of the bed bottom when it is to be swung to the stretched out position. At the 120 lower ends of the grooves 38 are respectively located stop blocks 38' which limit the downward movement of the bar 37, and support weight placed upon the seat 7, when the latter is in the closed position shown in Fig. 8. 125

In the folded position shown in Fig. 8, a portion of the mattress 4 and the outer section of the bed bottom, together with the

legs 30 and pillow rest 23 will be stored in the pocket at the back of the box frame. At this time, the seat 7 will be in its operative position, so that the back member 5 may be swung to the position shown in Fig. 8, thereby closing the pocket and covering the parts which are stored therein.

By having the bed bottom pivoted so as to swing bodily upon a single horizontal 10 transverse axis comprising the pins 20, a very simple and efficient structure is afforded, which eliminates much complicated mechanism.

For assisting in supporting the bed bottom in the stretched-out position, the seat 7 has attached to its rear edge one or more legs 40 which rest upon the floor when the seat is inverted, as shown in Fig. 2.

For holding the bed bottom closed, 20 against the opening effort of the springs 39, there is secured to the back of the box frame adjacent to the upper end thereof a vertical plate 41 having at its lower end a rearward extension 42, against the under side of 25 which is adapted to bear the adjacent edge of the pillow rest 23, as shown in Fig. 8. In opening the bed bottom, the back member 5 is swung to open position shown in Fig. 2, after which the outer section is 30 swung outwardly so as to free the pillow rest 23 from the locking device comprising the projection 42, whereupon the springs 39 will draw the bar 37 upwardly, thereby assisting the operator in swinging outwardly the seat section, which through the intermediate spacing bars 10, will force upwardly the inner section of the bed bottom. The pillow rest 23 and legs 30 are then 35 swung to the open position, so that when 40 the bed bottom is fully extended, the legs 30 and 40 will rest upon the floor.

I do not limit my invention to the structure shown and described, as modifications, within the scope of the appended claims, 45 may be made without departing from the spirit of my invention.

What I claim is:—

1. In a davenport, a box frame, and a bed bottom comprising a seat section, an inner 50 section and an intermediate section, said sections being pivotally connected with each other so as to swing from a folded position to a horizontal extended position, the seat section being hinged to the box frame independently and out of axial alignment with the pivotal connection between the sections, on an axis located intermediate of the upper and lower sides of the seat section, a bearing device carried by the box frame, 55 and a flexible supporting member supported by said bearing device and having a run-

ning connection therewith and having its ends secured respectively to the seat section and to the inner section and arranged to elevate and hold elevated the inner section 65 when the sections are swung from the folded to the stretched out position.

2. In a davenport, a box frame, a bed bottom hinged thereto and comprising a plurality of sections pivotally connected with each other so as to be swung from a folded position in the box frame to an extended horizontal position, a pillow rest carried by the bed bottom, and releasable means for lockingly engaging the pillow 75 rest with the box frame for holding the bed bottom in the folded position.

3. In a davenport, a frame, a bed bottom section hinged to the frame, a bed bottom section hinged to the first named bed bottom section, a support mounted on said frame, and a flexible supporting member connecting the two sections and supported by and having a running connection with said support, said flexible member being 80 85 adapted to cross the axis of the first named section when the latter is swung from one position to another.

4. In a davenport, a frame, two bed bottom sections hinged to each other, one of 90 the sections being hinged to the frame so as to swing from a stretched-out to a folded position and having means for engaging and limiting the swinging movement in one direction of the other section, and yielding 95 means for engaging and supporting said means for engaging means when the sections are swung to the folded position.

5. In a davenport, a frame, two bed bottom sections hinged to each other, one of 100 the sections being a seat section provided with an arm for engaging and limiting the swinging movement in one direction of the other section, and yielding means for engaging and supporting said arm, when the 105 seat section is swung to the operative position.

6. In a davenport, a frame, a seat section hinged thereto so as to be swung from an inverted to an operative position and having 110 two arms, an outer section hinged to said two arms, said arms limiting the swinging movement in one direction of the outer section relatively to the seat section, a transverse bar arranged to engage and support 115 said arms when the seat section is swung to the operative position, and yielding means for supporting said bar.

In testimony whereof I have signed my name to this specification.

PHILLIP W. BAIR.
